UNITED STATES PATENT OFFICE

PARK S. BRANT AND FRANKLIN THOMAS, OF FRIEDENES, PENNSYLVANIA, ASSIGNEES.
BY DIRECT AND MESNE ASSIGNMENTS, OF TWO-THIRDS TO SAID BRANT AND ONE-
THIRD TO LEE B. DUNCAN, OF ACOSTA, PENNSYLVANIA

NUT-SPLITTING TOOL

Application filed January 29, 1929. Serial No. 325,767.

The present invention relates to improvements in the art of tools, and more particularly, the invention has reference to a novel cutting tool especially adapted for splitting 5 nuts.

A tool of this character is very practical in use in salvaging old coal cars and various other structures, whereon the nuts have become firmly corroded or otherwise banded to 10 the bolts, so that it is necessary that the nuts be actually broken in order to remove the bolts.

The paramount object is to provide a tool of this character capable of exerting a powerful pressure against a nut in order to quickly 15 and safely split the nut so that the same may be displaced from the bolt.

Another object of importance, is to provide a cutting tool including a chisel element 20 removably associated with the tool.

Still another object is to provide a tool wherein cutting elements of varying lengths may be employed for cutting nuts of different dimensions.

25 These and other objects of the invention will become more apparent to the reader after considering the invention as described and claimed hereinafter.

In the drawings:—

30 Figure 1 represents a fragmentary top plan view of the improved tool.

Fig. 2 represents a fragmentary longitudinal sectional view of the jaws disengaged from the cutting element, and further showing 35 the cutting element in retracted position.

Fig. 3 is a fragmentary longitudinal sectional view showing the jaws engaged with the cutting elements, and showing the elements partially moved toward a nut to be 40 split.

Fig. 4 is an enlarged perspective view of one of the cutting elements.

Fig. 5 is an enlarged fragmentary perspective view of one of the jaw members.

45 Fig. 6 represents a fragmentary perspective view of an extension handle for the tool.

Referring to the drawings wherein like numerals designate like parts, a head generally referred to by the numeral 1, includes 50 a yoke 2 having an angular shaped protuber-

ance 3, at the inner edge of its bight portion.

The end portion of its legs are widened at 55 4 to provide a relatively narrow slideway 5, for the cutting bit 6. The opposite sides of the portions 4 of the yoke are covered by plates 7, which are secured to the yokes by suitable rivets 8. The rearward end of each plate 7 is provided with a pair of spaced ears 9—9.

Bolts 10 are disposed through the corresponding ears of the plates 7 for pivotally connecting a pair of jaws 11—11 to the head and between the plates 7 and a Y-shaped guide member 12 by the extremity of its legs to one of the plates 7. Nuts 13 may be applied to the bolts for securing these parts in proper order.

The cutting bit 6 is elongated and pointed at one end, while its opposite end is slightly flared as denoted by the numeral 14, and provided with a curved face 15. Adjacent the flared end of the bit, opposite longitudinal edges of the bit are formed with indentures 16—16.

70 The jaws 11—11 are each provided with a protuberance 17, for engagement within one of the indentures 16, while each jaw is further provided with a shoulder 18 having a curved space 19. The pivot point of each jaw is in eccentric relation to the axis of the curved face 19, so that when the shoulder 18 is moved toward the bit 6, the curved face 19 will exert a cam action against the curved face 15, of the bit, resulting in a rectilinear movement of the bit, in a direction toward 75 a nut disposed within the yoke member 2, of the head.

Each jaw 11 is provided with a shank extension 20, bifurcated at its outer end 21. A pair of bars 22—22 are pivotally mounted at their intermediate portions within the bifurcated ends of the shank 20, while one end of each is pivotally connected to the other, by means of an element 23 capable of slideable disposition within the slot 24, of the 80 guide member 12.

To afford a greater leverage for the jaws 11—11, an extension unit generally referred to by the numeral 25, is provided for each bar 22. Each extension unit consists of a 85

handle bar 26, provided adjacent one end with a pair of spaced boxes 27—27.

The boxes are open at their respective ends, so that the bar 22 may be disposed therethrough and secured by means 28.

5 It is preferable that the forward end portion of the yoke 2 be disposed obliquely so that the tool may be held away from the structure upon which the work is being conducted.

10 By properly disposing the yoke 2 over a nut to be split, and against the pointed protuberance 3, the bars 22 may be contracted so as to cause the swinging of the jaws 11—11. As the shank 20 of the jaws move 15 inwardly, the protuberances 17 on the jaws engaging in the indentures 16 of the bit 6, will cause the feeding of the bit 6 toward the nut and if desired, against the nut.

20 Subsequently, the shoulders 18 will engage the curved face of the bit 6 and through the cam action aforementioned, will exert a powerful rectilinear pressure against the bit 6, to split the nut. Certain specific changes 25 in the shape, size, and materials may be resorted to in the construction of this device without departing from the spirit and scope of the invention as claimed hereinafter.

Having thus described our invention, what 30 we claim as new is:—

35 A tool of the character described comprising a yoke shaped head, plates secured to opposite sides of the leg portions of the head, each plate being provided at one end with a pair of spaced ears, a Y-shaped guide member, the legs of the guide member being secured to the ears of one plate, said Y-shaped member being provided with a longitudinal slot, a pair of jaws pivoted between said plates, said jaws being each provided with a shank, a pair of levers, an element for pivotally connecting the levers together at one end, said element being engaged through the slot of the guide member, the outer ends of the shanks being pivotally 40 connected to said levers, a tool element slidably disposed within the head, and complementary means between the jaws and said tool whereby the tool may be urged against a nut disposed within the head.

45 50 In testimony whereof we affix our signatures.

PARK S. BRANT.
FRANKLIN THOMAS.
